CLARENCE C. STIRLING, OF HARTFORD, CONNECTICUT, ASSIGNOR TO THE HART & HEGE MANUFACTURING COMPANY, OF HARTFORD, CONNECTICUT, A CORPORATION OF CONNECTICUT.

ELECTRIC SWITCH.

1,278,781.

Specification of Letters Patent. Patented Sept. 10, 1918.

Application filed January 11, 1918. Serial No. 211,444.

To all whom it may concern:

Be it known that I, CLARENCE C. STIRLING, a citizen of the United States, residing at Hartford, in the county of Hartford and 5 State of Connecticut, have invented certain new and useful Improvements in Electric Switches, of which the following is a specification.

This invention relates to electric switches, 10 and more especially to that class thereof known as "snap switches." There are several kinds of these snap switches, and as may be inferred the improvement can be incorporated with advantage in any of them.

15 In the drawings accompanying and forming part of the present specification I have shown in detail a form of embodiment of the invention which to enable those skilled in the art to practice the same will be set forth 20 fully in the following description. I do not restrict myself, however, to this particular disclosure; I may depart therefrom in several respects within the scope of the invention defined by the claims following said 25 description. I have several fundamental motives in view. One is to furnish an article of the character set forth which is exceedingly compact. Another object I have in view is to provide for the efficient action 30 of the circuit-controlling member. There are other features of utility which I will set forth more in detail in said description.

Referring to said drawings:

Figure 1 is an elevation of a switch involving the invention.

Fig. 2 is a vertical transverse sectional view of the switch;

40 Figs. 3 and 4 are cross sections on the lines 3-3 and 4-4 respectively of Fig. 2, looking in the direction of the arrows applied to the respective lines.

45 Fig. 5 is a detail view of a circuit controlling or switching member and actuator, the parts being but partially represented and two positions thereof being illustrated by full and dotted lines respectively.

Like characters refer to like parts throughout the several views, Fig. 5 being on a larger scale than the other views.

50 The switch involves in its make-up a body generally made of some insulating material such as porcelain or even vulcanized rubber. The body shown is denoted by 2, and it is practically of cylindrical form. Surrounding the body is the shell as 3 of some sheet

metal and virtually of bell-shape and in which the insulating body 2 comparatively snugly fits, the shell being closed at its lower end by the cap 4, the two parts presenting a convenient casing for the insulating body 60 and coacting elements sustained thereby. As I have already stated the switch is shown as being of the pendent type; it may for example be carried by a cord consisting for instance of the wires 5 extending through an insulating ring or thimble 6 in the top of the shell 3 and connected to contacts or terminals mounted in some convenient way, one of which will be hereinafter set forth.

The body 2 is slotted from one end, as 70 shown the head or upper end, almost to the other end, the slot being denoted by 7 and being open on its sides in the periphery or circumference of said body. Said slot is virtually central of the transverse extent of 75 the body. The latter between its ends has a circumferential channel 8 in which are mounted the complementary contact members 9. These metal contact members 9 are of practically L or elbow shape and are perforated to receive screws as 10, the perforations being at the angles of the contact members. The screws 10 present a convenient way of connecting the wires 5 to said contact members. Their horizontal legs or branches extend forwardly and into the circumferential groove 8 and are of arched form for almost their complete length, to conform to the curvature of the body 2; their front or free ends are within the groove 8 and are 80 straight and practically in parallelism. These front straight portions constitute contacts, and are bridged in the organization shown, by the circuit controlling or switching member when the switch is in the on position as illustrated for example by dotted lines in Fig. 2.

The switching member which in the present case operates in the slot 7 is denoted in a general way by 12. It is of metal or other 100 conducting material and comprises a practically flat elongated body 13, from the sides of which extend outwardly or upwardly the two longitudinally separated pairs of co-operating flanges 14 and 15, the flanges 14 105 as shown being much longer than the flanges 15, although this is a detail which does not necessarily concern the invention. These flanges in the present case on their outer surfaces engage the walls of the slot or open- 110

ing 7 to thus maintain proper control of the circuit controlling or switching member 12.

This circuit controlling or switching member in the present case floats or moves bodily, having preferably a rocking or oscillatory movement as well as an endwise movement. It has as shown no direct connection with its actuator, although it is properly governed thereby in conjunction 10 for illustration with a suitable spring as 16. This spring 16 is of elongated coiled form and is under stretch and therefore action constantly. Its terminals are suitably held for instance by being united at its terminals with the shell 3. This spring also extends through registering perforations 17 in the flanges or lips 14 and is located in a slot 18 intersecting the main slot 7 and open at its outer ends, in view of which circumstance the spring may be connected to the shell as I have already noted.

The switching member 12 is maintained under proper control at all times by an actuator such as that denoted in a general 25 way by 19. This actuator can be made of some suitable insulating material and has a body or actuating portion as 20 which may be described broadly as being of cam form. It is shown as being in the shape of a wedge 30 with a slightly rounded apex, and is pivoted at 21 near its base in the slot 7 near what might be considered the lower end of the body 2. The actuator can, therefore, rock or oscillate.

35 The necessary rocking or oscillating motion of said actuator may be obtained in any desirable manner, for instance, by the buttons 22 and 23, which extend through registering perforations in the cap 4 and lower 40 portion of the body 2. The inner ends of these buttons extend into the main slot 7 and their lateral portions are within the circumferential channel 8 and engage the lateral projections 24 and 25 of the actuator 19. Other means might be substituted for buttons. I have already indicated that I am merely showing and describing a highly satisfactory form of structure comprising the features of the invention.

50 These buttons are not jointed or otherwise united with the actuator. They are really disconnected therefrom and have only a contact therewith to effect the necessary movement of the actuator. I prefer to provide therefore, means of a positive nature for controlling the buttons or equivalent means. In Fig. 2 the switching member 12 is supposed to be off and at this time is against the flat actuating face 26, the companion actuating face being designated by 27. In Fig. 5 the full lines show a corresponding position. To move the switching member 12 to the dotted line or on position of Fig. 2, the following procedure will be 65 adopted: The button 22 will be thrust up

or in, thereby elevating the projection 24 and consequently swinging the actuator 20 toward the right in said Fig. 2. On this particular motion the apex of the actuator will ride along the under surface of the 70 switching member and will first elevate the switching member. As the latter action occurs the spring 16 will be further stretched or tensioned. Continuing the apex of the actuator will traverse the under surface of the 75 switching member until the center line of the spring 16 is practically crossed. When this action does occur, the switching member is released and the stretched spring will snap the switching member forward 80 and downward to the closed position, so that the flanges or lips 15 can enter between the free ends of the contacts 9 as illustrated by dotted lines in Fig. 2. To open the circuit the action described will be exactly reversed.

Surrounding the inner or upper portions of the two buttons 22 and 23 are the hooks 28 constituting the ends of the arcuate spring 29, which fits in the circumferential 90 channel or groove 8 and between its ends bears against the body 2. These hooks and a part of the body of the spring conform in fact to the circumferential curvature of the two buttons and frictionally hold the 95 latter in positions to which they may have been shifted. The spring 29 is bodily immovable and as a matter of holding it against such action it may be fitted under one of the contact members 9.

What I claim is:

1. An electric switch comprising a floating switching member, and means for causing the rocking movement of said switching member successively between on and off positions.
2. An electric switch comprising a floating switching member, and manually operable means for causing the rocking movement of said switching member successively between on and off positions.
3. An electric switch comprising a floating switching member, and means including a spring, for causing the rocking movement of said switching member successively between on and off positions.
4. An electric switch comprising a floating rocking switching member, a spring acting as a pivot for the switching member, and means associated with the switching member to secure the movement thereof, by said spring successively between on and off positions.
5. An electric switch comprising a floating rocking switching member, a spring 125 acting as a pivot for the switching member, and means operative, against the switching member to effect movements of the same between on and off positions, through the action of the spring.

6. An electric switch comprising a switching member, spring means acting against the switching member and tending constantly to shift the same, and an actuator for causing successive rocking movements of the switching member to on and off positions through the action of the spring. 60
7. An electric switch comprising a floating switching lever, spring means acting against the switching lever, and actuating means to effect the movement of the switching lever by the spring means successively to on and off positions. 65
8. An electric switch comprising a floating switching lever, a spring extending through the switching lever and constituting a pivot therefor, and means operative against the switching lever to effect successive movements of the same between on and off positions through the action of the spring. 70
9. An electric switch comprising a floating switching lever, a spring extending through the switching lever between the ends thereof, and means to traverse the switching lever at opposite sides of the point thereof through which the spring extends to thus cause movements of the switching lever by the spring successively to on and off positions. 75
10. An electric switch comprising a switching lever, a spring extending through the switching lever to thus permit movement bodily thereof, and an actuator to engage and travel along the switching lever between opposite sides of the place at which the spring extends therethrough. 80
11. An electric switch comprising an oscillatory switching member, a coiled spring extending through the switching member between the ends thereof and secured at its ends to thus permit floating movement of the switching member, and a wedge-shaped oscillatory element shiftable manually to cause its opposite faces and apex to ride along the switching member to opposite sides of the point at which the spring extends therethrough. 85
12. An electric switch comprising switching mechanism, an actuator for said switching mechanism, buttons having lateral portions, supported independently of the actuator, to oscillate the same, and spring means acting against the lateral portions of the buttons to hold the same in their shifted positions. 90
13. An electric switch comprising switching mechanism, an actuator for said switching mechanism, buttons supported independently of the actuator to oscillate the same, and friction means acting against the buttons to hold the same in their shifted positions. 95
14. An electric switch comprising switching means, an actuator for said switching means, buttons supported independently of the actuator to oscillate the same, and spring means acting against the buttons to hold the same in their shifted positions independently of the switching means. 100
15. An electric switch comprising switching means, an actuator for said switching means, buttons supported independently of the actuator to oscillate the same, and a spring common to the two buttons and engaging the same, to hold both of them in each of their shifted positions. 105
16. An electric switch comprising switching means, an actuator for said switching means, a member having a lateral portion, supported independently of and disconnected from the actuator to engage and operate the same, and means acting frictionally against the lateral portion of said member to hold the same in a predetermined position. 110
17. An electric switch comprising switching means including a switching member and spring means, an actuator for tensioning said spring means to cause the snap movement of the switching member, a member supported independently of and disconnected from the actuator, said member being movable to effect the operation of the actuator, and means acting independently of said spring means and against the member to releasably hold it in a predetermined position. 115

In testimony whereof I affix my signature in the presence of two witnesses.
